UNITED STATES PATENT OFFICE.

WILLIAM H. EDWARDS, OF TERRE HAUTE, INDIANA.

DOOR-OPENER.

SPECIFICATION forming part of Letters Patent No. 767,555, dated August 16, 1904.

Application filed August 31, 1903. Serial No. 171,435. (No model.)

To all whom it may concern:

Be it known that I, WILLIAM H. EDWARDS, a citizen of the United States, residing at Terre Haute, in the county of Vigo and State 5 of Indiana, have invented certain new and useful Improvements in Door-Openers; and I do declare the following to be a full, clear, and exact description of the invention, such as will enable others skilled in the art to which

10 it appertains to make and use the same.

My invention is an improved door-opener adapted for use in opening and closing screen and other doors of houses and also adapted for use for opening and closing furnace and 15 other doors; and it consists in the construction and combination of devices hereinafter described and claimed.

The object of my invention is to provide an 20 improved apparatus for automatically opening and closing a door, so that a person wishing to pass through a door can open the same by stepping upon an operating-button.

A further object of my invention is to provide improved means for automatically closing 25 a door and for maintaining the same in a closed position.

In the accompanying drawings, Figure 1 is an elevation of a door-opener embodying my 30 improvements, showing the same applied to a screen-door. Fig. 2 is a top plan view of the same and a horizontal section through the screen-door. Fig. 3 is an inverted plan view of the same. Fig. 4 is a vertical transverse sectional view of the same, taken on the 35 plane indicated by the line $b-b$ of Fig. 3.

In the embodiment of my invention I provide a door-piece 1, which is adapted to be attached to a door a , as here shown. The said door-piece has a plate horizontally disposed, 40 having on one side a vertical flange 2, which bears against the outer side of the door at the bottom thereof and near its hinged side, and is secured thereto by screws 3 or other suitable devices. From the plate depend an outer 45 flange 4 and an inner flange 5, said flanges forming a raceway between them. The inner end of the flange 5 when the device is attached to a screen-door is here shown as cut away to form a clearance-space 6, as shown in Fig. 2, 50 for the purpose hereinafter described. When

the apparatus is used on a furnace or other similar door, the flanges 4 5 are coextensive in length.

A plate 7 of suitable size and which is adapted to be fastened by screws or other suitable devices on a platform or floor immediately outside of the door-sill and at the hinged side of the door, as here shown, is provided with bearings 8 9 for a vertical shaft 10. The bearing 9 is here shown as an angularly-shaped 55 hanger which depends from the plate 7. On the said shaft is a wheel 11, which may in practice be formed integrally therewith, if preferred. At the upper end of the said shaft and above the plate 7 is an arm 12 of suitable 60 shape. The said arm may be either angular in form, as here shown, or of any other suitable form. At its outer end and extending above it is a tappet device, which is here shown as an antifriction-roller 13, the same being 65 adapted to travel in the race-way of the door-piece 1. A strap 14, which in practice is preferably a metallic strap, passes around one side of the wheel 11 and is attached thereto, as at 15. 70

A link 16 has one end pivotally mounted in a bearing 17, which is here shown as secured to the under side of the floor or platform c . The said link travels in a supporting-guide 18, which is also secured to the under side of 80 the floor c , and on the link bears a brake device 19, which is here shown as a plate 20, which lies on the floor or platform c and has a centrally-disposed downwardly-extending flange 21, which extends through an opening 85 in the floor or platform and the lower edge of which is in contact with the upper side of the said link. The free end of the latter is provided with a pivoted keeper 22, in which is swiveled an adjusting-screw 23. The same 90 engages a threaded opening of a keeper 24, which is attached to one end of the strap 14. At the other end of said straps is an eye 25, which is engaged by a hook 26 at one end of a coil-spring 27. The opposite end of the 95 said spring is secured, as at 28, and the function of the said spring is to keep the strap 14 at the desired tension. The screw 23, which forms one element of the connection between the other end of the strap and operating-link 100

16, is for purposes of adjustment and also coacts with the spring 27 to vary the tension of the said strap.

An operating device 29 is here shown having a substantially vertical arm 30 and a substantially horizontal arm 31 at the upper end thereof, having an upturned outer end 32, provided with a button 33, the said button forming a head and adapted to be depressed by the foot of the operator. The lower end of the arm 30 of this operating device is here shown as pivotally mounted in a bearing 34 on a bracket 35. The said bracket is here shown as adapted to be secured at one end to the under side of the floor or platform *c* and at the other end to a joist or sleeper *d*. This bracket may be of any suitable construction, and I do not desire to limit myself in this particular. The upturned portion 32 at the outer end of the arm 31 of the operating device operates in the slot *e* in the floor or platform. A keeper 36 is pivotally connected to the operating device, as at 37, and has a threaded opening, which is engaged by the screw-threaded end of the rod 38. The opposite end of the said rod is swiveled to a keeper 39, which is pivotally connected, as at 40, to the link 16. The said screw-rod 38 has a suitable opening 41 for the insertion of a key, whereby it may be turned to adjust it. The screw 23 may be provided with a similar opening.

A spring 42 is here shown connected to the door *a*, the function of the said spring being to normally close said door. It will be understood that when the button 33 is depressed by stepping on the same pivotal movement is imparted to the operating device 29. The link 16 connected to the operating device is thus caused to move pivotally in one direction, and the same being connected to one end of the strap 14 draws the said strap in one direction against the tension of the spring 27, thereby imparting partial rotation to the shaft 7 and causing the arm 12 of said shaft to swing outwardly, whereby its tappet element, which travels in the raceway of the device 1, causes the door to open. When the pressure of the foot is relieved from the operating-button, the spring 27 acts on the strap 14 to return the operating device 28 and link 16 to their initial positions and to reversely turn the shaft 7 and permit the door to be closed by its spring. It will be understood that the spring which operates on the door to close it may be entirely dispensed with if the spring 27 is of suitable strength to close it, and that spring 27 will be effective, in connection with other elements of my improved door-operating apparatus, to maintain the door in a closed position. The clearance at the inner end of the flange 5 enables the door to be opened independently of the operating apparatus. When it is not desired that the door be adapted to be opened independently of the

operating apparatus, as when the latter is used on a furnace-door, the flange 5 will be coextensive in length with the flange 4, so that the tappet device will be under all conditions in engagement with the raceway of the device 1. 70

The function of the brake device is to hold the door open while a person is passing through the doorway. It will be understood that having opened the door by stepping upon the button 33 the person will then step with the other foot upon the plate 20, thereby holding the door open, and that upon raising his foot from the plate 20 the spring will immediately thereafter close the door behind him. 75

From the foregoing description, taken in connection with the accompanying drawings, the construction and operation of the invention will be readily understood without requiring a more extended explanation. 80

Various changes in the form, proportion, and the minor details of construction may be resorted to without departing from the principle or sacrificing any of the advantages of this invention. 85

Having thus fully described my invention, 90 what I claim as new, and desire to secure by Letters Patent of the United States, is—

1. In combination with door-operating means, including a lever and movable connections actuated thereby to open the door, and a spring to close the door, a brake device effective when pressure is applied thereto to frictionally engage a movable member of the door-operating connections and hold the door in open position against the tension of the 100 spring. 95

2. In combination with a door, having a device provided with a runway, a revoluble element having a tappet device slidable in the runway to operate the door, a strap to turn 105 said revoluble element, a pivoted link connected to one end of the strap, a tension-spring connected to the opposite end of the strap, an operating element connected to the link to move the strap against the tension of 110 the spring, and a brake device coacting with the link to lock the latter and thereby its coacting elements in position to hold the door open, substantially as described. 115

3. In combination with door-operating means, including a revoluble element having a detent, a device for attachment to a door, having a runway to extend below the door and for slidable engagement by the detent, said runway having a clearance-opening to 120 clear the detent and permit the door to be moved independently of the operating device, substantially as described. 125

In testimony whereof I have hereunto set my hand in presence of two subscribing witnesses.

WILLIAM H. EDWARDS.
